United States Patent

Des. 237,253
Patented Oct. 21, 1975

237,253

JUG

Peter L. Schweizer, Liberty Center, Ohio, assignor to
Owens-Illinois, Inc.

Filed Jan. 7, 1974, Ser. No. 431,283

Term of patent 14 years

Int. Cl. D9—01

U.S. Cl. D9—42

FIG. 1

FIG. 2

FIG.3

FIG.4

FIG. 5

FIG. 1 is a front elevational view of a jug showing my new design, the opposite side being a mirror image of the side shown;

FIG. 2 is a top plan view thereof;

FIG. 3 is an elevational view taken from the right of FIG. 1;

FIG. 4 is an elevational view taken from the left of FIG. 1; and

FIG. 5 is a sectional view taken through line 5—5 of FIG. 1.

I claim:

The ornamental design for a jug, substantially as shown and described.
